[57] CLAIM

The ornamental design for a lift-handle latch, as shown and described.

DESCRIPTION

FIG. 1 is a top, front, and right side perspective view of a lift-handle latch showing our new design;

FIG. 2 is a front elevational view thereof;

FIG. 3 is a top plan view thereof, the bottom being a mirror image of that shown;

FIG. 4 is a right side elevational view thereof;

FIG. 5 is a left side elevational view thereof;

FIG. 6 is a rear elevational view thereof;

FIG. 7 is a top plan view of a second embodiment thereof, the front and rear elevational views being identical in appearance to the first embodiment;

FIG. 8 is a right side elevational view of the second embodiment; and

FIG. 9 is a left side elevational view of the second embodiment.
